SHEET-METAL-FEEDING MECHANISM.

1,307,171.

Specification of Letters Patent. Patented June 17, 1919.

Application filed December 1, 1917. Serial No. 204,826.

To all whom it may concern:

Be it known that we, JESSE E. ABRAMS and GEORGE E. D. PARKER, citizens of the United States, residing, respectively, at 5 Canonsburg, in the county of Washington, State of Pennsylvania, and at Syracuse, county of Onondaga, and State of New York, have invented certain new and useful Improvements in Sheet-Metal-Feeding 10 Mechanisms, of which the following is a description, reference being had to the accompanying drawing and to the figures of reference marked thereon.

The invention relates to new and useful 15 improvements in sheet metal feeding mechanism, and more particularly to a feeding mechanism which is adapted to feed sheets of metal to a slitter.

An object of the invention is to provide a 20 feeding mechanism which operates automatically to present the sheets to the slitter disks and which also operates to position the sheet relative to said slitter disk, so that the sheet is fed evenly and that the resulting 25 strips may be uniformly shaped.

In the drawings which show by way of illustration one embodiment of the invention,—

Figure 1 is a plan view showing a portion 30 of a slitter having our improved feeding mechanism applied thereto;

Fig. 2 is a detail showing the mechanism for reciprocating the pusher in side elevation;

Fig. 3 is an enlarged plan view showing 35 the automatic means for delivering the sheet to the pusher and for squaring the sheet on the pusher prior to the delivery of the same by the pusher to the slitter disk;

Fig. 4 is an end view of the parts shown 40 in Fig. 3, viewed from the right of the figure;

Fig. 5 is an end view of the parts shown 45 in Fig. 3 from the other side of the machine; and

Fig. 6 is a front view showing the feeding-in rolls for delivering the sheet through the pusher and the supporting bed therefor.

The invention consists in an automatic 50 feeding mechanism, wherein the sheets of metal are delivered to a slitter, or some other mechanism adapted to operate upon the

metal, by a pusher which is reciprocated back and forth on the feeding-in table in proper timing for delivering the sheets to 55 the mechanism which operates upon the same. This pusher is provided with a rear gaging wall and an end gaging wall, so that the sheet may be gaged and properly presented to the operating mechanism. The 60 sheet is brought against the end gage by a reciprocating lever which engages the opposite end or side edge of the sheet prior to or while the pusher is moving forward. This seats the sheet metal against the end 65 gage. The sheet is seated against the rear gage by yielding fingers which lie in the path of travel of the sheet as the pusher moves forward. The sheet is presented to the pusher by feeding-in rolls which operate 70 continuously but which are intermittently separated, so as to intermittently operate upon the sheet. The sheet is placed between the feed rolls and in proper timing the feed rolls grip the sheet and feed it forward to 75 the pusher.

Referring more in detail to the drawings, Fig. 1 shows in plan view a slitter consisting of a supporting frame having end brackets 1, in which is mounted a shaft carrying the 80 slitter disks 2. The sheet to be cut is supported by the flexible supports 3. These parts are of the well known construction and further description thereof is not thought necessary.

The sheet to be cut is placed on a feeding-in table 4 and is slid along said feeding-in table to the slitter disk. The sheet is shoved on the table by a pusher 5, which is formed with a supporting ledge 6, a rear gaging 90 wall 7 and a side gaging wall 8. The pusher is also provided with slotted lugs 9-9 which are clamped by suitable bolts 10-10 to bars 11. These bars 11 are mounted to slide in grooves 12 formed in the table 95 4. The bars are provided with a series of holes 13 which receive the bolts 10, so that the pusher may be adjusted or shifted from one position to another to accommodate sheets of different sizes.

Mounted in suitable bearings in the frame is a shaft 14. This shaft has two upwardly projecting arms 15 and these arms are connected respectively by links 16 to an ear

17 clamped to the bars 11 on the underface thereof. The table is slotted to a certain extent, so as to permit these ears to slide back and forth and, therefore, when the 5 shaft 14 is oscillated the bars will be simultaneously moved toward and from the slitter disk. The shaft 14 is oscillated by a link 18, which is connected to a crank pin 19 on the face of disk 20, which disk is mounted 10 on the shaft carrying the upper slitter disk. The other end of the link 18 is connected to an arm 21 fixed to the shaft 14. The shaft 14 may, therefore, be oscillated in proper timing to the speed of the shaft carrying the slitter disk.

The slitter mechanism, together with this feeding-in table and pusher, above described, is well known in the art and further detail description of the construction and operation of the same is not thought necessary. The invention consists primarily in the feeding mechanism for placing the sheet on the pusher and the gaging mechanism which causes the sheet to engage the rear and end 20 gages of the pusher, so that it will be properly presented to the slitter disks.

Referring more in detail to Figs. 3 to 6, inclusive, there is shown means for moving each sheet sidewise in order to cause the 30 same to engage the end gage 8 on the pusher 5. This means includes a swinging rock lever 22. Said rock lever is pivoted at 23 to a suitable bracket mounted on the table 4. The arm 25 of the rock lever carries a 35 bumper 26 which is pivoted at 27 to the arm and is normally forced outwardly by a spring 28. A pin 29 carried by the bumper and extending into a slot 30 in the arm 25, limits the outward movement of this bumper. 40 The other arm 31 of the rock lever 22 is forked at 32 to engage a pin 33 on a sliding bar 34. This sliding bar moves back and forth in suitable brackets 35 and 36. Clamped to the bar 34 is a depending arm 45 37. This arm carries a sleeve through which extends the rod 38. Said rod is secured in the sleeve by a set-screw 40. The rod 38 also slides in suitable bearings in the brackets 35 and 36. A spring 41 is disposed between the sleeve on the arm 37 and the bracket 35 and normally forces the rod in the direction of the arrow, Fig. 4. At its inner end said rod carries a roller 42 which bears against a cam 43 on the shaft 44, which 55 supports the lower slitter disk. This cam is provided throughout a greater portion of its circumference with a concentric surface which leads into a depressed surface 45. As the cam rotates, the rod 39 will at times be 60 given a quick forward and backward movement and said movement of the rod will impart a quick oscillation to the rock lever 22. This causes the bumper 26 to engage the side of the sheet and move the same 65 against the side gage 8. Inasmuch as the

bumper is yieldingly mounted, the rock lever may have a positive throw without bending the sheet.

The sheet is moved against the rear gage 7 by yielding fingers 46. These fingers are 70 carried by a cross-shaft 47, and, as clearly shown in Fig. 3, there are two fingers one adjacent each end of the sheet. These fingers are secured to the cross-shaft 47 by suitable screws 48. This cross-shaft 47 is mounted in suitable brackets 50, one at each side of the table 4. The cross-shaft extends through one of these brackets and carries an arm 51 which is rigidly secured thereto. A spring 52 secured at one end to this arm 80 and at its other end to an extension at the base of the bracket 50, normally moves the arms, so that the same are held in contact with a stop pin 53. The lower ends of the fingers 46 extend into the grooves 12 in the 85 table. As the pusher moves forward, carrying the sheet along with it, the front edge of the sheet will strike these yielding fingers and this will move the sheet back until it comes in contact with the rear gage 7. The 90 fingers then yield to permit the sheet to slide underneath the same and be fed to the slitter disks.

It will be noted from the above that there is means provided for automatically gaging 95 the side edge of the sheet and for bringing the sheet into contact with said gage; also for gaging the rear edge of the sheet and for bringing the sheet into contact with said rear gage. If, therefore, a sheet of metal 100 is placed on the feeding-in table, anywhere in advance of the pusher, the machine will automatically position the sheet on the pusher and convey the same to the slitters. As a means for feeding the sheet on to the 105 feeding-in table, there are provided feeding rollers 54. These feeding rollers are mounted on a shaft 55. Co-operating with the two outer feeding rollers 54 are upper feeding rollers 56, which are mounted on a shaft 57 110 suitably driven. The shaft 55 is mounted in fixed bearings in the standard 58 which are secured to the feeding-in table 4. The shaft 57 is mounted in bearing sleeves 59, which are mounted to slide vertically in the 115 upper portions of the standard 58. Gears 59a connect the shafts 55 and 57. A spring 60 carried by each standard bears against the upper face of the bearing sleeve and normally tends to force the feeding rollers 56 into gripping contact with the feeding rollers 54. The tension of the spring 60 may be varied by the abutment screws 61. Mounted on each standard is a laterally projecting bracket 62. Mounted in the bracket 120 62 is a shaft 63. The shaft 63 carries two arms 64 which project rearwardly underneath the respective bearing sleeves at the ends of the shaft 57. The extreme ends of these arms 64 are rounded to engage the 125

65

bearing sleeves substantially directly underneath the center of the shaft and the spring 60. By oscillating the shaft 63 these arms 64 may be swung so as to raise the bearings 5 and the shaft 57 mounted therein and thus raise the feeding rollers 56 out of gripping contact with the rollers 54. The shaft 63, at one end thereof, carries an arm 65 which has a loose sliding connection at its lower 10 end with a lug 66 secured to a rod 67 which is mounted to slide in brackets 68 and 69 secured to the table 4. This rod 67 carries a roller 70 at its inner end which bears against a cam disk 71 mounted on the shaft 44. A 15 spring 72 secured at one end to the rod 67 and at its other end to the bracket 69, normally holds the roller 70 in contact with the cam. This cam is shaped so as to normally hold the rod 67 moved to the left until substantially a half rotation of the shaft 44, and while said rod is at its extreme left-hand position, the shaft 57 will be held raised, so that the feeding rolls 56 are ineffective. During the remainder of the rotation of the shaft 44, the feeding rolls 56 20 are dropped into co-operative action with the feeding rolls 54 and will grip a sheet placed between the rolls and deliver the same on to the feeding-in table in advance of the 25 pusher. In front of the feeding rolls is a raised sheet supporter 73. This sheet supporter has an end gaging plate 74 adjustably secured thereto by bolts 75 which pass through slots 76 into the sheet supporter. 30 The sheets may be stacked on this sheet supporter and are fed by an operator one at a time between the feeding rolls 54 and 56. No particular skill is required in feeding the sheet and an unskilled operator may, 35 therefore, place the sheets one at a time between the feeding rolls. In proper timing to the operation of the pusher the feeding rolls will grip the sheet and will quickly move the same forward on to the feeding-in 40 table in advance of the pusher. As the pusher moves forward the bumper 26 will be brought into contact with the side edge of the sheet moving the same laterally until it is in contact with the side gage 8. The forward movement of the pusher will cause the sheet to engage the fingers 46 and this will retard the movement of the sheet until it is in contact with the rear gaging member 7 and then the sheet will be properly presented to the slitter disks.

It is obvious that minor changes in the details of construction and arrangement of parts may be made without departing from the spirit of the invention as set forth in the appended claims.

Having thus described our invention what we claim as new and desire to secure by Letters Patent, is:

1. A sheet-feeding mechanism comprising 5 a reciprocating pusher having rear and side

gages, a reciprocating bumper for engaging the side edges of the sheet and moving the same laterally to cause the sheet to contact with the side gage, and yielding means for engaging the front edge of the sheet for causing the same to contact with the rear gage as the pusher moves forward.

2. A sheet-feeding mechanism comprising a reciprocating pusher having rear and side gages, a swinging arm having a yielding bumper mounted thereon for engaging the side edges of the sheet for moving the sheet laterally to cause the same to contact with the side gage.

3. A sheet feeding mechanism comprising a reciprocating pusher having rear and side gages, a swinging arm having a yielding bumper mounted thereon for engaging the side edges of the sheet for moving the sheet laterally to cause the same to contact with the side gage, yielding fingers located in the path of movement of the sheet for engaging the front edge thereof and causing said sheet to contact with said rear gage as the pusher moves forward.

4. A sheet-feeding mechanism comprising a reciprocating pusher having rear and side gages, a swinging rock lever, a pivoted bumper carried by one arm of said rock lever, a spring normally forcing said bumper outwardly, a stop limiting the outward movement of the bumper, means for oscillating said rock lever, said bumper being disposed so as to engage the side edges of the sheet and move the same laterally to cause the sheet to contact with the side gage.

5. A sheet feeding mechanism comprising a reciprocating pusher having rear and side gages, a swinging rock lever, a pivoted bumper carried by one arm of said rock lever, a spring normally forcing said bumper outwardly, a stop limiting the outward movement of the bumper, means for oscillating said rock lever, said bumper being disposed so as to engage the side edges of the sheet and move the same laterally to cause the sheet to contact with the side gage on the pusher, yielding fingers located in front of the sheet and in the path of movement thereof for engaging the front edge of the sheet to retard the movement of the same and cause the rear edge of the sheet to contact with the rear gage.

6. The combination of a feeding-in table and a reciprocating pusher for moving the sheets on the feeding-in table, said pusher having side and rear gages, of means for yieldingly engaging the side edge of the sheet for moving the same laterally to cause said sheet to contact with the side gage, and means for engaging the front edge of the sheet for causing the sheet to contact with the rear gage, feed rollers for feeding the sheet to the feeding-in table in advance of

the pusher, said feed rollers being arranged in opposed pairs, and means for lifting the upper feed roller from gripping contact with the lower roller for rendering the same ineffective at intervals.

- 5 7. The combination of a feeding in table and a reciprocating pusher for moving the sheets on the feeding-in table, said pusher having side and rear gages, of means for
- 10 yieldingly engaging the side edge of the sheet for moving the same laterally to cause

the same to contact with the side gage, means for engaging the front edge of the sheet for causing the sheet to contact with the rear gage, opposed feed rollers for feeding the 15 sheet on to the feed table in advance of the pusher, and means for intermittently rendering said feed rollers ineffective.

In testimony whereof we affix our signatures.

JESSE E. ABRAMS.
GEORGE E. D. PARKER.
